UNITED STATES PATENT OFFICE.

JOHN P. PARDUE, OF ST. LOUIS, MISSOURI.

SECRETARY.

SPECIFICATION forming part of Letters Patent No. 279,004, dated June 5, 1883.

Application filed January 24, 1883. (Model.)

To all whom it may concern:

Be it known that I, JOHN P. PARDUE, of St. Louis, in the State of Missouri, have invented a new and Improved Secretary, of which the following is a full, clear, and exact description.

The object of the invention is to construct a secretary with convenient receptacles for the desk and other things ordinarily used therewith, as hereinafter described.

Reference is to be had to the accompanying drawings, forming part of this specification, in which similar letters of reference indicate corresponding parts in all the figures.

Figure 1 is a perspective view of my new and improved secretary as it appears when open and the book-support A swung out for use. Fig. 2 is a sectional elevation of the same, taken on the line *x x* of Fig. 1, showing the parts as they appear when the secretary is closed; and Fig. 3 is a perspective view of the book-support and the means for supporting and operating it removed from the secretary.

The main body or inclosure B of the secretary may be of any suitable size and form, and may be ornamented in any desired manner to suit the taste, and it is by preference divided internally into compartments by the horizontal partitions *a* and *b*. In the upper compartment, formed by the partition *a* and the top *a'* of the secretary, is placed the book holder or support A, which is attached near its lower edge, by means of the staple *d*, to the apex of the triangular rod C, and near its center, by the plate *d*, to the bent crank-rod D, both of which rods are journaled at their ends, the rod D above the rod C, in the outer side walls of the secretary, as clearly shown in Fig. 1. One end of the rod D passes some distance through one of the said side walls, and is provided outside of the inclosure with the crank *f*, as shown in Figs. 1 and 3, by which the book-support A may be swung out of the secretary to the position shown in Fig. 1, for holding a book open in front of the reader sitting at the desk G, or carried back into the upper compartment of the secretary, as shown in Fig. 2. The space in the said upper compartment not occupied by the book-support A may be utilized in any suitable manner; but I prefer to place in it the side pigeon-holes, E E, and to place centrally upon the partition *a* the roof-shaped partition

F, under which, upon the partition *a*, may be set ink-bottles, sponge-cups, &c., as shown, and to which may be attached the corresponding cleats, *c c*, for holding the small drawer H. 55 Above the drawer H is formed, by the small horizontal portion *e*, a small triangular compartment for the reception of pen-holders, pencils, rulers, &c.

In the compartment formed between the partitions *a* and *b*, I place the drawer J, which is well adapted for holding papers, pamphlets, periodicals, &c.

The lower compartment, formed by the partition *b* and the bottom *b'* of the secretary, is 65 divided into side compartments by the vertical partition *k*, which compartments are well adapted for holding bound volumes of text and reference books. The compartments are adapted to be closed by the door K. The desk G 70 performs a twofold function—that of furnishing a table or desk on which to write and that of a door for closing the upper compartment of the secretary. It is by preference made of two parts, which are hinged together, as shown, so 75 as to furnish a narrow or wide writing table or desk, as desired. When raised up for closing the secretary it is held in that position by means of the perforated spring-metal plates *i i*, which catch upon the pins *i' i'*, driven into the 80 edges of the table, near its upper edge, as shown in Fig. 1; or any invisible catch may be used. The book-support is by preference provided with the elastic bands *h h*, which may be put over the leaves of the book, as shown clearly 85 in Fig. 1, for holding the book open and the leaves from turning of their own accord. The book having been placed upon the support A, and the support and book having been carried back into the secretary and the secretary closed, 90 in order to bring the book into position for reading, it is only necessary to let down the table or desk G and apply the hand to the crank *f* and turn it forward, which will cause the bent rod D to first carry the support A slightly 95 upward, and then cause it and the triangular rod C to move outward and downward until the inner edge of the book-support rests upon the apex of the triangular partition F, in which position the rod C and partition F will hold 100 the support in a slightly-inclined position, thus holding the book in a most convenient position

for a person sitting at the desk to read and take notes.

In order to replace the book-support and book back in the secretary, it is only necessary 5 to apply the hand again to the crank *f* and turn it backward, which will cause the rod *D* to carry the support and the rod *C* upward and backward into the secretary to the position shown in Fig. 2, where it may be closed in by 10 the table *G*, perfectly secure against all danger of molestation. In this manner it will be seen that the book is not only held in a convenient position for the reader and all things necessary for writing and taking notes kept handy in the 15 secretary, but that the book, when replaced in the secretary, is held open at the place where the reader left off, so that when the book is brought out again the reader may begin his work again from the place where he stopped 20 at the previous reading.

It is designed to provide the legs or supports of the secretary with casters, so that it may be easily moved from place to place in an office or room.

Having thus described my invention, what I 25 claim as new, and desire to secure by Letters Patent, is—

In a secretary, the combination of the main body of the same, having partition *a* and top *a'*, the triangular partition *F*, the triangular 30 rod *C*, the rod *D*, having crank *f* on the outside, and the book-holder *A*, attached near its lower edge to the rod *C* and near its center to the rod *D*, said rods being journaled in the body of the secretary above the triangular partition *F*, as shown and described. 35

JOHN P. PARDUE.
